CURTAIN CONFINER

Filed May 28, 1929

Fig. 1.

UNITED STATES PATENT OFFICE

CATHERINE ROGERS, OF TAUNTON, MASSACHUSETTS

CURTAIN CONFINER

Application filed May 28, 1929. Serial No. 386,746.

The object of this invention is to provide means for confining a portion of a shirred curtain in a predetermined position relative to a window with which the curtain is associated, whether the curtain be of full length and is secured to the upper end of the casing and formed to depend therefrom to the lower end, or is a semi-curtain or overdrapé, secured at its upper edge to the upper end of the casing and formed to depend therefrom a distance less than the vertical length of the casing and serve as an adjunct for a full length curtain.

Of the accompanying drawings forming a part of this specification,—

Figure 1 is a side view of a window provided with two full length curtains and a semi-curtain or overdrapé, and confining means for each of said curtains.

Figure 2 is a side view of the confiner associated with the full length curtains shown by Figure 1.

Figure 3 is a section on line 3—3 of Figure 1.

Figure 4 is a section on line 4—4 of Figure 3.

Figure 5 is a section on line 5—5 of Figure 2.

Figure 6 is a section on line 6—6 of Figure 2.

Figure 7 is a perspective view of the hinge socket member hereinafter described.

Figure 8 is a perspective view of the impaling rod hereinafter described, and the hinge pintle member thereon.

Figure 9 shows in perspective an enlargement of a portion of the overdrapé shown by Figure 1, and one of the confiners associated therewith.

Figure 10 is a section on line 10—10 of Figure 9.

Figure 11 is an enlargement of a portion of Figure 10.

Figure 12 is a fragmentary sectional view similar to a portion of Figure 10, showing a modification.

Figure 13 is a sectional view, showing another modification.

The same reference characters indicate the same parts in all of the figures.

I will first describe the confiner associated with a full length curtain and shown by Figures 1 to 8 inclusive.

12 designates a full length curtain which may be a member of a pair of curtains shown by Figure 1, each curtain being attached at its upper end in any suitable manner to the top of a window casing 13, and formed to extend to the bottom of the casing, each curtain and the confiner associated therewith being similar in all essential respects to the other, so that a description of one will suffice.

The confiner in this embodiment of the invention is adapted to hold the curtain either in the position shown at the left, or that shown at the right in Figure 1, the lower portion of the curtain in one case hanging beside the lower portion of the window, and in the other case, removed from the window and hanging beside the lower portion of the casing and an adjacent portion of the wall.

The confiner comprises a rod 14, adapted to be inserted in or thrust through the folds 12^a constituting a shirred portion of the curtain 12, as shown by Figures 3, 5, and 6, the rod having at its outer end a penetrating point 14^a (Figure 6) and a stop 15 detachably secured to the pointed end portion and adapted to prevent an end fold of the curtain from slipping from the outer end of the rod, the stop 15 being preferably a nut engaged with a screw-thread on the pointed end portion.

The opposite end of the rod is provided with a hinge pintle member adapted to turn in a hinge socket member fixed to the casing, so that the confiner and curtain may be adjusted to partly cover the lower portion of

the window, or to expose said portion, as shown by Figure 1.

The hinge members are preferably formed to constitute a ball and socket joint, the pintle member being a ball 16 fixed to the inner end of the rod, while the socket member 17 is a cup formed to receive the ball, and having a flange 18 adapted to be attached to the window casing, as by screws 19, passing through slots 20 in the flange. The socket member 17 has a slot 21 through which the rod 14 extends, the ends of the slot constituting stops which limit the turning movements of the ball and the swinging movements of the rod.

15. When the socket member is attached to the window casing, a shirred portion of the curtain is impaled on the rod 14, and its outer fold is confined by the stop 15. The shirred portion and rod may then be adjusted to

20 either of the positions shown by Figure 1. To assist in maintaining the pintle member or ball 16 by friction in either of its adjusted positions, I provide a resilient metal strip 23, located in the socket member or cup 17, and 25 in frictional contact with the ball, as shown by Figure 4.

The confiner preferably includes a finishing strip, adapted to conceal the portions of the rod which may be visible between the folds 14, and assist in maintaining said folds symmetrically arranged. Said strip may be of any suitable material, and ornamented if desired. The length of the strip is preferably such that it includes two elongated longitudinal stretches 24, adapted to bear on the folds 12 at both sides of the shirred portion, as shown by Figures 3, 5, and 6, and conceal rod portions between adjacent folds, and a transverse portion 25 adapted to be penetrated by the rod 14.

The inner end of one of the stretches 24 is preferably provided with an extension 24' extending across and concealing the hinge member 17, and secured to the flange 18 by means such as a hook 36 (Figures 3 and 5) formed on said flange, the strip being of flexible penetrable material and of sufficient width to cover the hinge. The inner end of the other stretch 24 may be secured to the flange 18 by a hook 37. The opposite transverse portion 25 is engaged with the rod and confined by the stop member 15, as shown by Figure 6.

The folds of a shirred semi-curtain or over-drape 26, shown at the upper portion of Figure 1, and in part by Figures 9 to 13, may be confined at intervals by a plurality of vertically arranged confiners, each embodying the features of the confiner above described, excepting the hinge members.

In this embodiment of the invention, each confiner comprises a rod 27 having a pointed end 28, adapted to penetrate the folds of the shirred semi-curtain 26, and provided with

a stop nut 29 engaged with the pointed end portion of the rod and with another stop 30, which is preferably a nut, engaged with the opposite end portion.

A finishing strip 31 is engaged with the rod, as best shown by Figure 10. The semi-curtain and the confiners are, in this instance, supported by a horizontal bar 32, engaged at its ends with brackets 33, (Figure 1) attached to the casing 13, the bar extending through the upper portions of the semi-curtain and finishing strip and preferably through loops 34 formed by the upper edge portion of the semi-curtain. The finishing strip 31 may be formed to entirely embrace a portion of the shirred semi-curtain, as shown by Figures 9, 10 and 11, or to bear on only one side thereof, as shown by Figure 12.

Figure 13 shows a finishing strip 38, which may be pressed from sheet metal and is provided at one end with an ear 39, to which one end of the rod 27 is secured, and at the opposite end with an ear 40, receiving the pointed end of the rod 27, and forming a seat for the stop nut 29. The strip 38 may be provided with bead-like ornamental bosses 41 at its outer side, and with spurs 42 at its inner side, adapted to engage folds of the semi-curtain 26, as shown. The ear 39 and the portion of the rod 27 fixed thereto, form a recess through which the bar 32 extends to support the confiner and semi-curtain.

I claim:

1. A curtain confiner comprising a rod adapted to penetrate the folds of a portion of a shirred curtain and provided with a detachable stop at its penetrating end, means associated with the opposite end of the rod for supporting it in a predetermined position, and a finishing strip engaged with the rod and adapted to extend across the shirred curtain portion and conceal exposed portions of the rod.

2. A curtain confiner comprising a rod adapted to penetrate the folds of a portion of a shirred curtain and provided with a detachable stop at its penetrating end, means associated with the opposite end of the rod for supporting it in a predetermined position, and a finishing strip engaged with the rod and adapted to extend across the shirred curtain portion and conceal exposed portions of the rod, said strip being formed as a cincture adapted to embrace the shirred portion.

3. A curtain confiner comprising a rod adapted to penetrate the folds of a portion of a shirred curtain and provided with a detachable stop at its penetrating end, the opposite end of the rod being provided with a hinge pintle member and with a hinge socket member attachable to a window casing, and having means for limiting turning movements of the pintle member and swinging movements of the rod.

4. A curtain confiner comprising a rod

adapted to penetrate the folds of a portion of a shirred curtain and provided with a detachable stop at its penetrating end, the opposite end of the rod being provided with a ball-shaped enlargement constituting a hinge pindle member, and with a cupped socket constituting a hinge socket member, and provided with an attaching flange, and with a slot having ends adapted to limit turning movements of the ball and swinging movements of the rod.

10 In testimony whereof I have affixed my signature.

CATHERINE ROGERS.
